COMBINED CLOSURE CAP AND POURER FOR BOTTLES

George Clare, Maplewood, N. J.

Application February 1, 1955, Serial No. 34,310

Term of patent 14 years

(Cl. D58—10)

FIG. 4

FIG. 2

FIG. 1

FIG. 3

FIG. 5

Fig. 1 is a side elevation of a combined closure cap and pourer for bottles showing my design;

Fig. 2 is a rear elevational view thereof;

Fig. 3 is a front elevational view thereof;

Fig. 4 is a top view thereof; and

Fig. 5 is a bottom view thereof.

I claim:

The ornamental design for a combined closure cap and pourer for bottles, substantially as shown.
